P. V. TAMIETTI.
SIGNAL FOR VEHICLES.
APPLICATION FILED APR. 3, 1919.

1,336,106.

Patented Apr. 6, 1920.

UNITED STATES PATENT OFFICE.

PETER V. TAMIETTI, OF MONROVIA, CALIFORNIA.

SIGNAL FOR VEHICLES.

1,336,106.

Specification of Letters Patent.

Patented Apr. 6, 1920.

Application filed April 3, 1919. Serial No. 287,126.

To all whom it may concern:

Be it known that I, PETER V. TAMIETTI, a citizen of the United States, residing at Monrovia, in the county of Los Angeles and State of California, have invented a new and useful Signal for Vehicles, of which the following is a specification.

My invention relates to a signal for motor vehicles of the class adapted to give notice 10 that the vehicle is about to turn.

An object of my invention is to provide a signal of this class which will be readily discernible from some distance at night or in the day time.

15 Another object of my invention is to provide a signal of this character which can be readily affixed to a vehicle at a point conveniently accessible for the operator of the vehicle.

20 Another object of this invention is to provide a signal of this class which will be of a simple construction and durable and sure in operation.

In the drawings:

25 Figure 1 is a plan view of my signal with one of the signal arms in extended position.

Fig. 2 is a vertical section of the same.

Fig. 3 is a detail illustrating the method 30 of attaching my signal to the frame of a vehicle.

Fig. 4 is a section taken on line indicated by x^4-x^4 , Fig. 2.

Fig. 5 is a diagram illustrating the electric circuit used in the signal.

35 Referring to the drawings, there is represented at 1 a cylindrical hollow shell. Mounted within the shell 1 are two cylindrical hollow tubes 2, each of a diameter equal to approximately one-half of the diameter of the shell 1. The tubes 2 are closed 40 at one end by a wall 3 and are inwardly threaded at their opposite ends 4.

Each of the tubes 2 is provided with a longitudinal hollow rod 5, which rod is provided at one end with a collar 6, the collar 6 being preferably screw-threaded onto the end of the rod 5 and of a diameter corresponding to the inner diameter of the tube 2. Mounted at the end of each of 50 the tubes 2 is a coil spring 7 which is adapted to abut against the collar 6 of the rod 5 and tend to force the rod 5 from without the tube 2. The threaded end 4 of the tubes 2 is closed by a cap 8 screw-threaded there- 55 in, which cap is apertured to slidably en-

gage the rod 5. The rod 5 is of a greater length than the tube 2 and is provided at its outer end with signal means comprising an electric globe 9 having a socket 10 mounted within the tube and a guard 11 surrounding the globe 9. In addition to the electric globe 9 the end of the rod is provided with a flag signal 12 adapted for use particularly in the day time. The flag signal 12 comprises a cloth 13 secured to the rod 5 and the guard 11 and to a wire 14 which is bent in a double vane surrounding the guard 11. A flat extensible spring 15 surrounds and registers with the wire 14 and is secured at its ends to the rod 5. The spring 15 is provided with clips 16 to retain the rod 14.

The collars 6 are provided with arms 17 which are slidably received within longitudinal slots 18 formed in the shell 1, which slots are provided with bayonet extensions 19 at their ends and the arms 17 are formed with convenient handles 20.

The circuit for the electric globes 9, as indicated at Fig. 5, is formed by the sockets 80 10 contacting with the edge of the rods 5 forming a ground. Wires 22 lead from the globe 9 through the rods 5 and are connected to the contacts 23 which are mounted in the collars 6, the contacts 23 projecting 85 slightly from the collars and the collars 6 being preferably of insulating material. Secured to the caps 8 within the tubes 2 are bushings 24 in which are mounted contacts 25 spaced to register with and contact with 90 the contacts 23 when the springs 7 are in extended position. The contacts 25 are provided with connections 26 which extend without the shell 1. From the connections wires 27 lead to one terminal of a switch 28. 95 The opposite terminal of which switch is connected to one terminal of a battery 29. The opposite terminal of which battery is grounded as illustrated in Fig. 5.

The tubes 2 are preferably secured within 100 the shell 1 by set screws 30 and the shell 1 is adapted to be secured to the frame preferably adjacent the steering wheel of the vehicle by means of a bracket 31, as illustrated in Fig. 3.

105 The operation of the signal is as follows: The shell 1 is of a length approximately equal to the width of the vehicle. When the vehicle is being operated along a straight road the arms 17 are secured within 110

the bayonet extensions 19. The springs 17 are exerting a tension against the collar 6 which tends to slide the rod 5 through the cap 8 and extend the end of the rod and 5 signal means without the shell 1. If the operator of the vehicle intends to turn, he grasps one of the handles 20 and moves the arm 17 from without the bayonet extension 19. The rod will be freed and the spring 15 10 will slide the rod through the cap 8 until the collar 6 abuts the bushing 24. As the signal end of the rod leaves the shell 1 the spring 15 carrying the cloth 13 will expand, forming a double vane which acts as a warning that the vehicle is about to close and 15 when the rod 5 is in an extended position the contacts 23 and 25 will complete the circuit and the globe 9 will be illuminated.

After the vehicle has made the turn the 20 operator will grasp the handle 20 and return the arm 17 to the bayonet extension 19 from which it was originally released. This will be accompanied by a compression of the spring 7 and the rod will be withdrawn 25 within the shell 1. As the spring 15 enters the shell 1 it will abut against the edge of the shell and the edge of the opposite tube 2 and will be contracted as illustrated in Fig. 2 of the drawings.

30 It is understood that the two rods provide for signaling that the vehicle is about to turn to the right or to the left. If the vehicle is to be turned to the left one of the handles 20 is operated as above described 35 and if it is to be turned to the right the other handle 20 is so operated.

My invention is not limited to the details of construction heretofore described, but is of the breadth and scope set forth in the 40 subjoined claims.

I claim:

1. A signal for vehicles comprising a shell, two tubes superposed within said shell, each of said tubes being provided with a 45 signal carrying rod, means within said shell to project said signals from without said

shell, and slots in said shell receiving means to operatively control said rods.

2. A signal for vehicles comprising a shell, tubes superposed within said shell having one of their respective ends closed, rods mounted in each of said tubes, collars upon said rods, caps for said tubes apertured to slidably receive said rods, spring means mounted between the ends of said tubes and said collars to force said tubes from without said shell, and signal means carried by said rods.

3. A signal for vehicles comprising a shell, rods slidably mounted within said shell, means to extend said rods from said shell, means to control the movement of said rods, electric globes carried by said rods, means to illuminate said globes, and vanes carried by said rods surrounding said globes, 65 said vanes being surrounded by an extensible spring means.

4. In a signal for vehicles the combination of an elongated shell, tubes superposed within said shell having one of their respective ends closed, rods mounted within said shell and adapted to project therefrom, signal means carried by said rods, collars upon said rods slidably received within said tubes, springs mounted between said collars and the ends of said rods adapted to propel said rods into extended position, slots formed in said shell, arms carried by said rods slidably received within said slots, bayonet extensions of said slots adapted to receive said arms to secure said rods in retracted position against the action of said springs, and caps mounted at the ends of said tubes and slidably receiving said rods to limit the extended position of said rods.

Signed at Los Angeles, California, this 28th day of March, 1919.

PETER V. TAMIETTI.
